SASH LOCK FOR BUS OR CAR WINDOW
CONSTRUCTIONJoseph Schunk, Union, N. J., assignor to The
National Lock Washer Company, Newark, N. J.,
a corporation of New Jersey

Application June 23, 1944, Serial No. 541,813

3 Claims. (Cl. 292—173)

1

The present invention relates to a sash lock for bus or car window construction, and has for an object to provide a bolt actuating sash lock assembly which may be conveniently incorporated in the bottom rail of a window sash, with the co-operative parts of the lock secured to the bottom rail entirely at one side of the sash lock bolt, as distinguished from prior types of sash locks, wherein the attaching screws for the sash lock assembly extended through the bolt, necessitating the punching of clearance slots therein.

A further object is to provide a sash lock case of substantially reduced thickness having a continuously flat face in spaced parallel relation to the flat surface of the bottom rail, its shape and construction eliminating the necessity for the usual projecting bulge offset heretofore provided in the case for containing the operating lever. The flat face greatly facilitates cleaning, and has the further advantage of increasing the sill surface and minimizing the possibility of a person catching his hand or fingers between the sill and the sash lock case when the sash is lowered.

A further object is to provide an improved sash lock assembly wherein the sash lock lever, of relatively wide flat form, is pivotally arranged in parallel relation in the space between the inner side of the flat sash lock case and the flat side surface of the bottom rail, so that regardless of its position effectual support for the lock lever is obtained.

With the above and other objects in view, an embodiment of the invention is shown in the accompanying drawing, and this embodiment will be hereinafter more fully described with reference thereto, and the invention will be finally pointed out in the claims.

In the drawing:

Fig. 1 is a fragmentary view, showing the inner side of one lower corner of a window sash in which is incorporated the sash lock assembly, according to the illustrated exemplary embodiment of the invention.

Fig. 2 is a horizontal sectional view, taken along the line 2—2 of Fig. 1.

Fig. 3 is a longitudinal vertical sectional view, taken along the line 3—3 of Fig. 2.

Fig. 4 is a transverse vertical sectional view, taken along the line 4—4 of Fig. 1.

Fig. 5 is a vertical transverse sectional view of the bottom rail, taken through the sash lock mounting portion thereof, the sash lock parts being removed.

Fig. 6 is a detail plan view of the sash lock bolt.

2

Fig. 7 is a side elevation thereof.

Fig. 8 is a side elevation of the sash lock insert or frame member.

Fig. 9 is a transverse vertical sectional view thereof, taken along the line 9—9 of Fig. 8.

Fig. 10 is a detail side elevation of the sash lock case.

Fig. 11 is a transverse vertical sectional view thereof, taken along the line 11—11 of Fig. 10.

Fig. 12 is a side elevation of the sash lock lever.

Fig. 13 is an edge view thereof.

Similar reference characters indicate corresponding parts throughout the several figures of the drawing.

15 Referring to the drawing, the window sash, in which the sash lock assembly of the invention is incorporated, comprises generally a sash glass 10, a top rail (not shown), a bottom rail, and a pair of vertical side straps connecting the top 20 and bottom rail. Only one end of the bottom rail and one of the side straps is illustrated, it being pointed out that the other end of the window sash is of identical construction, an identical sash lock being carried thereby in reversed relation 25 to the sash lock illustrated. The side straps are adapted to have vertical sliding movement in vertical sash guide post pieces at each side of the window opening, the sash lock bolts in each end of the bottom rail engaging rack strips provided 30 in the post pieces.

The bottom sash rail comprises a pair of spaced side strips 11—11, between which is secured by welding or the like a sash glass receiving channel strip 12 having its upper edges flush with the upper edges of the strips 11. A second channel strip 13 is secured between the side strips 11 intermediate their lower edges and the base of the channel strip 12, the space between the channel strips 12 and 13 providing a longitudinal passage 40 through the bottom rail in which the sash lock bolt is engaged, as will presently more fully appear. At the lower edges of the side strips 11 there are provided inwardly projecting flanges 14, engaged with the longitudinal side grooves 15 45 of the rubber weather strip 16 inserted in the longitudinal pocket provided below the channel strip 13. Instead of forming the bottom rail from the several strips as shown it may be of extruded one-piece form, or of other suitable structure to provide substantially the same cross-sectional shape. A vertical recess 17 is provided in the end of the bottom rail for receiving the lower end of the side strip, as will presently more fully appear, this 50 recessed end being formed by extending the ends 55

of the side strips 11 beyond the ends of the channel strips 12 and 13 and the flanges 14.

The side strap comprises a channel strip 18 adapted to receive the vertical edge of the glass 10 and the glazing strip 19 enclosing it, its vertical side walls being bent outwardly and rearwardly at their forward edges to provide flanges 20-20 to engage the forward vertical sides of the facing strip 21 engaged about the channel strip. The facing strip is of U-shape cross-section and is formed of suitable sealing material, such as felt, being cemented or otherwise suitably secured about the channel strip. The lower end portions of the flanges 20 are compressed, as at 22, and are engageable within the end recess 17 of the bottom rail, with the end of the rubber weather strip 16 of the bottom rail extended into engagement with the vertical bottom wall of the channel strip 18, the side strap having secured to it an inwardly projecting lug member 23, engaged in the end of the longitudinal passage of the bottom rail and secured to the rail by a screw 24. This lug member is of inverted U-shape in cross-section at its projecting portion engaged within the bottom rail, so that it engages over the top and sides of the sash lock bolt, while its portion 25 within the channel strip 18 is of rectangular tubular form. The upper and lower walls of the tubular portion 25 are provided with lug extensions 26-26, engaged through a rectangular opening 27 in the vertical base of the wall of the channel strip and bent above and below the slot into contact with the outer surface of the base wall where they are rigidly secured thereto by welding or the like. In axial line with the opening 27 and the passage through the tubular portion 25 of the lug member the facing strip 21 is provided with a rectangular passage 28, the outer end of the sash lock bolt being slidably engaged in these passages and normally projected therefrom into engagement with the rack strip of the sash guide post piece with which the side strap of the window sash assembly is normally engaged.

At its sash lock locating point the bottom rail is provided at its inner side with a pivot bearing hole 29, and an arcuate slot 30, concentric to the axis of the bearing hole and directly beneath it, the bearing hole being relatively near the upper edge of the rail and the arcuate slot being at a point opening into the bolt-receiving passage of the rail for receiving the bolt actuating lug of the sash lock lever, as will presently more fully appear. The rail is also provided as its inner side with three holes 31 suitably located to receive the attachment studs and screws of the sash lock assembly, as will presently more fully appear.

The sash lock assembly comprises an insert or frame member 32 in the form of an elongated rectangular strip engageable within the longitudinal passage of the bottom rail in contact with the inner surface of the inner side strip 12 thereof, being of suitable width to fit between the under surface of the channel strip 12 and the upper edge of the channel strip 13. The insert member is provided in its upper edge in position to substantially register with the arcuate slot 30 of the bottom rail with a rectangular cut out 33, and at suitably spaced points with counter-sunk holes 34 in which are engaged flanged internally threaded bushings 35. These bushings are flush with the inner surface of the insert member and project from the outer surface to engage within the holes 31 of the bot-

tom rail, where they are engaged by the attaching screws 36 of the sash lock case 37. At its rearward end the insert member is bent inwardly at a right angle to provide a stop and guide 38 for the extension rod of the sash lock bolt, a bearing passage 39 being provided therein for receiving the rod.

A stepped thrust pad member 40 is secured to the inner side of the insert member, by welding or the like, and projects downwardly therefrom to seat within the groove of the channel strip 13, the angular step 41 thereof engaging over the corner of the inner flange of the channel strip 13. This thrust pad is adapted to be contacted by the bolt when the end of the bolt is supported on the sash rack and the weight of the raised window is imposed thereon.

The sash bolt 42 is in the form of an elongated bar of rectangular cross-section, provided at its outer end with a rack engaging beveled nose 43 and near its rearward end and at its upper side with a rectangular notch 44 for receiving the actuating lug of the sash lock lever, as will presently more fully appear. An extension rod 45 is provided upon the inner end of the plunger and has engaged thereon a U-shape straddler or pressure member 46, an aperture 47 being provided in the intermediate portion of said member for sliding engagement upon the rod, and the sides of the member embracing the end of the plunger. The straddler member is normally pressed forwardly toward the end of the plunger by means of the plunger spring 48 disposed about the rod 45 between the straddler member and a washer 49 slidably mounted upon the end of the rod and retained thereon by means of an enlargement 50 formed upon the end of the rod. It should be noted that the enlargement 50 serves to retain the washer, spring, and straddler member in place upon the plunger when these parts are in disassembled relation as a unit, as shown in Figs. 6 and 7. In the assembled relation in the sash rail the rod 45 is engaged through the passage 39 of a stop guide 38. In the assembled relation of the parts the washer 49 abuts the stop guide 38 compressing the spring 48, the stop guide acting as a fixed part against which the spring reacts.

The sash lock case 37, which has a continuously flat outer face parallel to the inner side of the bottom rail, is provided with an inwardly bent rim flange 51 extending along its horizontal lower edge and upwardly along its inwardly curved end edges, the upper side of the case being open to provide a slot opening for the bolt actuating lever and having a horizontal lip 52 extending outwardly therefrom at a right angle to provide a finger grip for cooperation with the lever, as will presently more fully appear. The lower wall of the rim flange 51 has a pair of supporting lugs 53 lanced therefrom and bent upwardly at each side of the central attaching screw receiving hole 54, so as to provide a bracing structure at the central area of the case to withstand the tightening force of the central screw 36.

A pivot stud 55 is riveted to the inner side of the case and is engaged in the pivot hole 29 of the bottom rail to provide a pivot mounting for the sash lock lever 56, a bearing bushing 57 being secured in the lever for engagement with the stud. At its upper edge the lever is provided with an outwardly projecting finger grip lip 58 vertically opposed to the lip 52 of the case. At its lower edge there is provided an inwardly projecting bolt actuating lug 59, engaged with the notch 44 of

the bolt through the arcuate slot 30 of the rail and the cut out 33 of the insert member 32.

The straddler member 46 is pressed back in the assembled relation, as shown in Figs. 1 to 4, so that its forward edges are substantially in line with or slightly forward of the edge of the notch 44, and normally presses against the lever lug 59, which in turn is pressed against the opposed side of the notch 44. In this way the lock parts and the operating lever are at all times held against looseness and rattling under pressure of the spring 48, the straddler member being so arranged that it takes up all lost motion and compensates for wear and variations in the parts. This condition obtains even after considerable wear upon the parts and also under the continuous vibration to which the parts are subjected in the usual bus and car installations. The bolt is retracted through downward pressure upon the lip 58 of the lever causing the lug 59 to swing rearwardly in the slot 30 and thus retract the bolt against the pressure of the spring.

The lever 56 is in the form of a relatively wide plate, its forward edge being extended in a wide curve from the forward edge of the lip 58 to the lug 59, so that in any position a substantial surface of the lever is effectually supported in the narrow space between the opposed parallel surfaces of the bottom rail and the sash lock case.

It will be observed that the mounting structure of the sash lock assembly is arranged entirely upon the inner wall of the bottom rail and at the inner side of the sash lock bolt. Hence, it is unnecessary to punch slots in the bolt for receiving the threaded bushings and screws for the sash lock assembly, as heretofore required. The flat face of the sash lock case provides a relatively large clear space between the lip 52 and the window sill so that there is little possibility of catching a finger between the casing and the sill in the lowering of the window.

I have illustrated and described preferred and satisfactory embodiments of the invention, but it will be obvious that changes may be made therein, within the spirit and scope thereof, as defined in the appended claims.

Having thus described my invention, what I claim and desire to secure by Letters Patent is:

1. In a sash lock window construction, a rail having inner and outer side walls and a longitudinally extending bolt passage, said inner wall of said rail having a slot, a lock bolt disposed in said passage and projected from one end, a lock case member engaged upon the outer side of said inner wall, attaching means securing said case to said inner wall terminating between said case and the inner side of said bolt, and an operating lever pivotally mounted in said case having an actuating lug extended through said slot into engagement with said bolt.
2. In a sash lock window construction, a rail having inner and outer side walls and a longitudinally extending bolt passage, said inner wall of said rail having a slot and a plurality of screw receiving holes, a lock bolt disposed in said passage and projected from one end, a lock case member engaged upon the outer side of said inner wall, attaching screws connected between said inner wall and said case extending through said screw receiving holes and terminating between said case and the inner side of said bolt, and an operating lever pivotally mounted in said case having an actuating lug extended through said slot into engagement with said bolt.
3. In a sash lock window construction, a rail having inner and outer side walls and a longitudinally extending bolt passage, said inner wall of said rail having a slot and a plurality of screw receiving holes opening to said passage, a lock bolt disposed in said passage and projected from one end, an insert frame member engaged upon the inner side of said inner wall, a lock case member engaged upon the outer side of said inner wall, attaching screws connected between said insert member and said case extending through said screw receiving holes and terminating between said case and the inner side of said bolt, and an operating lever pivotally mounted in said case having an actuating lug extended through said slot into engagement with said bolt.

JOSEPH SCHUNK,
